UNITED STATES PATENT OFFICE.

IRENAEUS P. NELSON, OF HAMILTON, OHIO, ASSIGNOR OF ONE-HALF TO
NAPOLEON B. TUBBS, OF SAME PLACE.

ROLLER-SKATE.

SPECIFICATION forming part of Letters Patent No. 319,839, dated June 9, 1885.

Application filed February 24, 1885. (No model.)

To all whom it may concern:

Be it known that I, IRENAEUS P. NELSON, of Hamilton, Butler county, Ohio, have invented certain new and useful Improvements 5 in Roller-Skates, of which the following is a specification.

This invention pertains to roller-skates for parlor, rink, and pavement use, and it relates particularly to the mechanism of the roller-trucks.

My invention will be readily understood from the following description, taken in connection with the accompanying drawings, in which—

15 Figure 1 is a side elevation of a roller-skate embodying my improvements, the forward left-hand wheel or roller of the skate being omitted so as to expose more fully the truck mechanism, all straps and other foot-fastenings being also omitted; Fig. 2, an elevation 20 of the inside face of one of the trucks, shown upon an enlarged scale and viewed in the direction indicated by the arrow *a* of Fig. 1; and Fig. 3, an elevation of one of the springs, 25 shown in modified form.

In the drawings, *A* represents the usual foot-board of a roller-skate; *B*, the trucks, one secured near the heel and one near the toe, as usual; *C*, the hangers of the trucks, secured in 30 the usual manner to the foot-board; *D*, a rocker-pin supported in the hanger, one in each hanger, and forming the axis of oscillation for the wheel-housing; *E*, the wheel-housing, formed, in the case illustrated, of a cast tube; 35 *F*, a housing-horn cast with the housing *E* and projecting upward and engaging the rocker-pin *D*; *G*, the wheel-axes secured within and projecting from each end of the housing, *E*; *H*, the wheels or rollers, of which there are 40 four, one upon each end of each axle; *I*, foot-shoulders formed by a shelf-like projection cast upon the housing *E*; *J*, rods hung to the hangers and projecting downward through the foot-shoulders, there being two rods for 45 each truck, one disposed on either side of the rocker-pin; *K*, an adjusting-nut at the upper end of each rod; *L*, springs surrounding the rods and disposed between the adjusting-nuts and footing-shoulders, and *M* swing-pivots at 50 the top of the rods engaging lugs on the lower

surface of the hanger-plate. The rocker-pins *D* are disposed angularly, as is usual, whereby the tipping of the skater's foot serves to force the two wheel-axes of the skate in non-parallel planes, and thereby cause the skate to move 55 in a curved path. The yielding of the spring permits the oscillation of the skate-bottom with reference to the horizontal plane of the wheel-axes, and by means of the adjusting-nut the springs may be altered to suit the requirements of the skater. It is the office of the springs to normally hold the skate-bottom parallel to the horizontal plane of the wheel-axes, under which conditions the two axles 60 of the skate should be in parallel vertical 65 planes. The tension of one of the springs of the truck may be increased or decreased, so that the accuracy of this position will be normally maintained. The adjusting-nuts form abutments for the upper ends of the springs, 70 and the nuts serve to correct inequalities in the length or strength of the springs. Should accurate manufacture insure equal length and strength of the springs and a proper degree of elasticity for the skater's requirements, the 75 nuts need never be adjusted, and may, if desired, be formed as rigid unadjustable shoulders. As the rocking motion takes place the rods within the springs slide through the footing-shoulders, and the swing-pivots at their tops 80 prevent them from impeding the rocking motion.

In Figs. 1 and 2 the springs are shown as helical springs acting under compression. These may, however, act tensionally by securing 85 their bases to the footing-shoulder, and by arranging the adjusting-nuts to act upon them tensionally instead of compressively. Such arrangement is illustrated in Fig. 3.

I have chosen for illustration a well-known 90 form of skate in which the hangers are separably secured to the foot-board; but my improvements are equally applicable to metal-bodied skates having the hangers cast integrally with the foot-piece.

I claim as my invention—

1. In a roller-skate, a hanger below the foot-piece of the skate, a wheeled housing attached thereto by a rocker-pin, a pair of springs disposed one on each side of the rocker-pin and 95 100

serving to maintain the normal relative positions of the foot-piece and the housing, and rods and adjusting-nuts or their mechanical equivalents for adjusting said springs, combined substantially as and for the purpose set forth.

2. In a roller-skate, a hanger below the foot-piece of the skate, a wheeled housing attached thereto by a rocker-pin, a pair of rods engaging the hanger and projecting downward through footing-shoulders upon the housing, and springs surrounding said rods, combined substantially as and for the purpose set forth.

3. In a roller-skate, a hanger below the foot-piece of the skate, a wheeled housing attached thereto by a rocker-pin, a pair of rods engaging the hanger, and footing-shoulders upon the housing, springs surrounding the rods, and adjusting-nuts upon the rods above the springs, combined substantially as and for the purpose set forth.

IRENAEUS P. NELSON.
